GLOVE

Frank Sperandeo, Brooklyn, N. Y.

Application November 7, 1940, Serial No. 364,609

4 Claims. (Cl. 2—169)

This invention relates to new and useful improvements in a glove.

More specifically, the invention contemplates the construction of a glove which is characterized by a one piece trunk having a back panel with four finger portions for the backs of the four fingers, a front thumb side portion, and a front small finger side portion.

More specifically, the invention proposes that the said front thumb side portion be provided with a complementary index finger portion continuing into a thumb back portion, in turn continuing into a quirk portion.

Another object of the invention resides in characterizing the front small finger side portion by providing it with a complementary small finger portion.

In one form of the invention it is contemplated to provide separate second and third complementary front finger portions arranged in a particular manner.

In another form of the invention it is contemplated to arrange the second and third complementary finger portions as an integral part of the one piece trunk.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Figure 1 is an elevational view of a glove constructed in accordance with this invention and viewed from the palm side.

Fig. 2 is an elevational view of the glove shown in Fig. 1 viewed from the back side.

Fig. 3 is a horizontal sectional view taken on the line 3—3 of Fig. 1.

Fig. 4 is a developed view of the one piece trunk used in constructing the glove shown in Figs. 1-3.

Fig. 5 is a developed view of the separate second finger complementary front portion used in the glove.

Fig. 6 is a developed view of the separate third finger complementary front portion used in the glove.

Fig. 7 is a developed view of one piece trunk of a glove constructed according to a modification of this invention.

Fig. 8 is a developed view of one of the four-

chettes intended to be used in conjunction with the trunk shown in Fig. 7.

The glove, in accordance with the form of the invention illustrated in Figs. 1-6 inclusive, includes a one piece trunk as illustrated in Fig. 4, having a back panel 10 with four finger portions 11, 12, 13 and 14, and having a front thumb side portion 15 and a front small finger side portion 16. The said front thumb side portion 15 has a complementary index finger portion 17 continuing into a thumb back portion 18, which in turn continues into a quirk portion 19. The front small finger portion 16 has a complementary small finger portion 20.

15 The trunk described in the prior paragraph is intended to be used in conjunction with a separate second finger complementary front portion 21 which continues in a complementary thumb front portion 22. In addition there is a separate third finger complementary front portion 23 continuing into a portion 24 extending slightly down the palm of the glove. These various parts are jointed together at their adjacent edges with seams as thereafter more fully described.

25 The seams of the glove may be better comprehended by examining Figs. 4, 5 and 6, visualizing the manner in which the glove is folded and stitched. The blank shown in Fig. 4 is folded along the line AB. Then the sections 11 and 17 30 of the index finger are superimposed. The section 17 has a side extension portion 17a, defined by the dot and dash line 17', to give the necessary depth to the index finger. The sections of the index finger are seamed together along their 35 free edge portions.

The separate second finger complementary front portion 21 is provided with side portions 21a defined by the dot and dash line 21'. These side portions 21a are bent backwards and their free 40 edges are seamed to the free edges of the second finger portion 12. These side portions 21a give the necessary depth for the second finger. The adjacent edges 17aa and 21aa of the side portions of the index finger and second finger are seamed 45 together.

The thumb portion 18 is bent downwards upon the dot and dash line 18a and then the edge 21b is seamed to the edge 17b and the edge 21c is seamed to the edge 18c, and the edge 20d is seamed to the edge 18d to the points 21e and 18e, respectively. The edge portion 21f is seamed to the edge portion 18f.

The third finger complementary front portion 23 is superimposed on the third finger back section 13. The third finger portion 23 has side

portions 23^a divided off by the dot and dash lines 23'. These side portions extend backwards and are seamed at their edges to the edges of the third finger portion 13. The adjacent edges 21^{bb} and 23^{bb} of the second and third finger portions are seamed together. The edge 21^c is seamed to the edge 24^c.

The front side small finger portion 16 is bent over on the line CD. The edge 24^b is seamed to the edge 16^b. The small finger portion 20 is provided with a side portion 20^a defined by the dot and dash lines 20'. This side portion 20^a provides depth for the small finger. It is extended rearwards and seamed along its edges to the free edges of the small finger portion 14. The edge 20^{aa} is seamed to the edge 23^{aa}. The bottom edge 24ⁱ of the palm section 24 is seamed to an area 19ⁱ of the quirk portion 19. The side 19ⁱ of the quirk 19 is seamed to the edge 16ⁱ. The side 15^k of the front thumb side 15 is seamed to the side 16^k of the front small finger portion 16. The back panel 10 is provided with ornamental stitches 28.

The dominating feature of the glove resides in the fact that the palm side of the second finger continues into the palm side of the thumb. Moreover, the third finger continues into the palm.

In Figs. 7 and 8 another form of the invention has been disclosed which distinguishes from the prior form in several respects. In this form it is intended that fourchettes be used at the sides of the fore finger. Moreover, the second and third finger portions are arranged integral with the one piece trunk. More specifically, in the form of the invention shown in Fig. 7, the one piece trunk includes a back panel 30 provided with four fingers 31, 32, 33 and 34, a front thumb side portion 35 and a front small finger portion 36.

The said front thumb side portion 36 has a complementary index finger portion 37 which at the bottom continues into a front thumb portion 38, which continues into a quirk portion 39. The front small finger portion 35 is provided with a complementary small finger portion 40, a complementary third finger portion 41, and a complementary second finger portion 32. At the side the front small finger portion 35 continues into a complementary thumb portion 43.

The blank shown in Fig. 7 is intended to be folded on the lines EF and GH. Fourchettes, such as the fourchette 45 illustrated in Fig. 8, are intended to be seamed to the open sides of the four fingers to give depth to these fingers. The usual piecettes, not shown on the drawing, are intended to be seamed between the bottom ends of adjacent fourchettes 45. The back panel 30 is provided with ornamental stitches 46. The free edge portions of the front portions 35 and 36 are seamed together along the sides indicated by identical small letters ranging from "a" to "f" inclusive. It is believed that the complete seaming together of the glove will be readily understood from this description.

While I have illustrated and described the preferred embodiments of my invention, it is to be understood that I do not limit myself to the precise constructions herein disclosed and the right is reserved to all changes and modifica-

tions coming within the scope of the invention as defined in the appended claims.

Having thus described my invention, what I claim as new, and desire to secure by United States Letters Patent is:

1. A glove, comprising a one piece trunk having a back panel with four finger portions for the backs of the four fingers, a front thumb side portion and a front small finger portion, said front thumb side portion having a complementary index finger portion continuing into a thumb back portion continuing into a quirk portion, said front small finger portion having a complementary small finger portion, a separate second finger complementary front portion continuing into a complementary thumb front portion, and a separate third finger complementary front portion continuing slightly down the palm, and seams joining adjacent edges together.
2. A glove, comprising a one piece trunk having a back panel with four finger portions for the backs of the four fingers, a front thumb side portion and a front small finger portion, said front thumb side portion having a complementary index finger portion continuing into a thumb back portion continuing into a quirk portion, said front small finger portion having a complementary small finger portion, a separate second finger complementary front portion continuing into a complementary thumb front portion, and a separate third finger complementary front portion continuing slightly down the palm, and seams joining adjacent edges together, the front small finger portion and the front thumb side portion of said one piece trunk being provided with side portions to give depth to these fingers.
3. A glove, comprising a one piece trunk having a back panel with four finger portions for the backs of the four fingers, a front thumb side portion and a front small finger portion, said front thumb side portion having a complementary index finger portion continuing into a thumb back portion continuing into a quirk portion, said front small finger portion having a complementary small finger portion, a separate second finger complementary front portion continuing into a complementary thumb front portion, and a separate third finger complementary front portion continuing slightly down the palm, and seams joining adjacent edges together, said separate second finger complementary front portion having side portions to give depth to this finger.
4. A glove, comprising a one piece trunk having a back panel with four finger portions for the backs of the four fingers, a front thumb side portion and a front small finger portion, said front thumb side portion having a complementary index finger portion continuing into a thumb back portion continuing into a quirk portion, said front small finger portion having a complementary small finger portion, a separate second finger complementary front portion continuing into a complementary thumb front portion, and a separate third finger complementary front portion continuing slightly down the palm, and seams joining adjacent edges together, said separate third finger complementary front portion having side portions to give depth to this finger.
